KEY RING

Max Brunner, Chicago, Ill.

Application June 9, 1953, Serial No. 360,470

1 Claim. (Cl. 70—458)

The present invention relates to key rings and more particularly is directed toward an improved key ring which provides a positive key-retention means for preventing confusion of the keys mounted thereon.

Key rings, in the well known circular form, have been known for centuries. However, the prior art devices of which I am aware held the keys loosely on the ring and hence permitted the keys to move completely around the key ring when the key ring was held loose in the pocket. In view of the fact that no reliance could be placed on the position of the key on the key ring, it was essential for the user of the keys to memorize the shape of the key head or the particular configuration of the lock actuating surface of each key.

While use of the keys on one of the above described key rings might be accomplished with relative ease during daylight hours or wherever an adequate amount of light was provided, there are few people who can identify keys in the absence of light by their mere lock actuating notches or head shapes. The result of this has been, therefore, that the very simple key ring type of container for keys is rarely used where more than one or two keys must be carried.

By the apparatus of the present invention, all of the above objections are overcome by providing a simple key ring which positively prevents any shifting of the keys. It is then a simple matter to locate an individual key by remembering only its position on the ring rather than its particular shape. Since location of the key on the key ring is the determining factor in locating the key, it is also contemplated that keys having no large heads thereon may be utilized with the present key ring. The absence of such heads greatly reduces the weight of the keys and hence provides an extremely practical key and key ring combination which persons ordinarily adverse to the use of key rings will readily accept.

It is therefore an object of the present invention to provide a simple key ring having abutments secured thereto for preventing the keys thereon from shifting their relative position.

Another object of the present invention is to provide a key ring of a simple and inexpensive nature which will permit selection of the desired key through knowledge only of its constant position on the key ring.

Yet another object of the present invention is to provide a key ring which is readily adapted to keys not provided with the usual enlarged heads.

A feature of the present invention is a provision of a key ring which may be utilized as the handle for a substantially headless key, as well as a carrying means therefor.

Another feature is the provision of a key ring constructed of a single piece of wire and capable of preventing realignment of the keys carried thereby.

Still another object of the present invention is to provide a novel key ring which will combine with substantially headless keys to provide an extremely compact key and key ring combination.

2

Still other and further objects, will at once become apparent to those skilled in the art through a consideration of the attached drawings in which several modifications of the present invention have been shown by way of illustration only.

On the drawings:

Figure 1 is a plan view of a key ring constructed according to the present invention and having a plurality of keys thereon;

Figure 2 is a cross sectional view taken along the line II—II of Figure 1;

Figure 3 is a side elevation view of the key ring shown in Figures 1 and 2, with one of the keys positioned for use;

Figure 4 shows a modified form of the key ring of the present invention;

Figure 5 is a cross sectional view taken along the line V—V of Figure 4.

Figure 6 shows another modification of the key ring constructed according to the present invention; and

Figure 7 shows a side elevation of the key ring shown in Figure 6 with one of the keys positioned for actuation of a lock.

As shown on the drawings:

The key ring shown in Figures 1 through 3 comprises a loop of wire like material, preferably spring steel of a relatively high quality. This loop, as may be seen from Figure 1, has a polygonal configuration in which all of the sides of the polygon are formed by overlapping portions of the spring material with the exception of a single side. As is shown in these figures the loop is shown to be constructed of a single piece of wire having a first end section 1 and a second end section 2 with an intermediate portion 3 positioned therebetween. The end section 1 of the wire is joined to the intermediate section 3 by the portions 4, 5, and 6 of the wire, while the end section 2 is joined to the intermediate portion 3 through the sections 7, 8 and 9.

A plurality of keys 10 are provided having heads 11 of a relatively small size. In view of the comparatively small size of the heads of keys 10 relative to the heads of the usual commercial key, they are generally termed "headless" keys and will be referred to as such herein. Each of the keys is provided with an aperture 12 which is of a diameter slightly greater than the diameter of the wire from which the key ring is constructed. Thus, as may be seen from a consideration of Figure 2, the key will permit a single strand of the wire to pass through its aperture 12 and will not permit the passage of the overlapped portions of the key ring. Thus, key retaining abutments 13 and 14 are provided by the free ends of the end sections 1 and 2 of the key ring material.

In order to place the keys on the straight bar portion 3 of the key ring the usual procedure, familiar to all those who have used prior art key rings, is utilized. For example, section 1 of the ring is pried apart from the section 9 and the key is positioned on section 1 by means of its aperture 12. The key is then moved along the wire from portion 1 to portion 4, to portion 5, to portion 6 and from there around the corner to the left hand end of portion 3 as viewed in Figure 1. This procedure is then followed by each successive key until a full complement of keys is provided.

Since a very small head is provided on the keys, a very large number of keys may be placed on the key ring without difficulty. Thus, while the key ring is not shown to be completely full in Figures 1 and 2, the key ring of the present construction permits a full complement of keys to be positioned on the section 3 such that the abutments 13 and 14 are constantly in contact with the keys. However, it is of course realized that only one or two keys, if desired, may be carried on the key ring of the

present invention. In this case, it is contemplated that the end sections 1 and 2 can be bent inwardly to restrict the key-carrying portion 3 and prevent the keys from moving back and forth.

In use of the key ring for unlocking a door or similar article, all of the keys except that key to be utilized, designated 10a in Figure 3, are folded back against the key ring. While it is of course possible to pivot all of the keys into a position on one side of the key ring such as shown at 10b of Figure 3, it is desirable to pivot a part of the keys to the left as shown at 10b and the rest of the keys to the right as shown at 10c. The keys may then be gripped by the fingers so that an operating handle formed by the keys 10b, 10c and the key ring is provided for the key 10a.

A further modification of the key ring is shown in Figures 4 and 5 in which the key ring 20 is formed in a rectangular shape. An advantage of the rectangular shape as shown in Figure 4 is that the keys may be folded completely back within the key ring when it is desired that the key ring be carried in the pocket or when a single key is to be utilized in opening a lock.

As shown in Figure 5, the key ring of Figure 4 is not constructed in the form of completely round wire at the points of overlap. By machining the surfaces 20a and 20b flat, the section 3a need not be positioned at an angle to the plane of the ring and further, the width of the ring at the overlapping portions may be reduced. It is of course understood that this construction may be utilized with the various other ring shapes such as for example, that shown in Figure 1.

In this connection it is to be noted that various shapes can be provided for the key ring, including triangular or circular shapes. The rectangular shapes are preferred however, since they permit the keys to be folded backwardly upon the key ring during the use of a single key to a greater extent than such shapes as the triangle. While this is true it is within the concepts of the present invention to use such other shapes even though slightly less convenient than the shapes shown in Figures 1 and 4.

Figures 1 through 4 are somewhat enlarged and it is intended in actual practice that the key ring such as shown in Figure 1 have outer dimensions of the usual key head now sold commercially. Thus through the use of the novel key ring with the substantially headless keys as shown in Figures 1 and 4, the actual key ring with the keys thereon takes up little more space in the user's pocket than a single ordinary key would require. This is an important advantage, since it is desirable in all instances to reduce the volume as well as the weight of the keys and key ring as much as possible so as not to interfere with other articles which are to be carried in the pocket.

Figures 6 and 7 show a third modification of the present invention in which the key ring comprises a ring 21, and a tubular key support 22.

In this modification, the keys 10 are permanently mounted on the key supporting tube 22 which is subsequently peened over at its ends 23 and 24 to retain the

keys in position thereon. The abutments provided by the flanged over ends 23 and 24 positively prevent the keys from moving relative to each other about the key ring 21, and hence it is impossible for the keys to become mixed up or otherwise to change their relative position on the key ring.

As shown in Figure 7, the keys 10b and 10c and ring 21 provide an actuating handle for the key 10a which is being utilized. This handle is effective since the tube 22 is positioned in the apertures 12 in a rather snug manner, thereby providing a direct turning effect between the keys 10b and 10c and the remaining key 10a.

While only three keys are shown on the tube 22 in Figure 5, it is contemplated that any number of keys may be utilized in this manner. For example, the tube 22 may be sufficiently long to accommodate 10 or 12 keys with ease. In this latter case, however, it may be desirable to substitute a chain for the ring 21 or to dispense with a ring or chain entirely.

It will thus be apparent that I have provided a novel key ring construction in which abutments are provided on the ring to positively prevent keys from indiscriminately moving around the ring. This construction has proved highly advantageous since it permits the use of substantially headless keys and also permits the identification of the desired key in the dark since the keys retain their originally set position on the key ring indefinitely.

It will be understood that modifications and variations may be made to the above described structure without departing from the novel concepts of the present invention.

I claim as my invention:

A key ring comprising a loop of material overlappingly wrapped, said loop having a substantially straight intermediate portion at which no overlapping occurs, and a plurality of keys mounted on said intermediate portion, the holes in said keys having a diameter less than the combined diameter of the key ring in its overlapping portion but greater than the diameter of the key ring material of said intermediate portion whereby the keys may be positioned on said intermediate portion and will be prevented from movement away from said intermediate portion by the ends of the overlapping portions of said ring.
